(57) **CLAIM**

The ornamental design for a speaker having slidable base, as shown and described.

DESCRIPTION

FIG. 1 is a perspective view of a speaker having slidable base showing a first embodiment our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in use;

FIG. 10 is a perspective view thereof showing an electronic apparatus supported on the slidable base and leaned on the main body;

FIG. 11 is a perspective view of a speaker having slidable base showing a second embodiment our new design;

FIG. 12 is another perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a perspective view thereof in use; and,

FIG. 20 is a perspective view thereof showing an electronic apparatus supported on the slidable base and leaned on the main body.

The broken line subject matter in FIG. 10, and FIG. 20 is included for the purpose of illustrating unclaimed environment and forms no part of the claimed design. The broken line portions of the speaker having slidable base in all views represent unclaimed portions of the claimed design and form no part thereof.

1 Claim, 20 Drawing Sheets
